(57) **CLAIM**

The ornamental design for a rear end portion of truck body, as shown and described.

DESCRIPTION

FIG. 1 is a front perspective view of a rear portion of truck body showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a first side elevational view thereof; and,

FIG. 7 is a second side elevational view of the truck body section of FIG. 1.

The broken lines in the drawings are provided to illustrate the environment of the claimed invention and do not form a part of the claimed invention.

1 Claim, 3 Drawing Sheets

FIG. 2.

FIG. 3.

FIG. 4.

FIG. 5.

FIG. 6.

FIG. 7.
